UNITED STATES PATENT OFFICE.

GRANVILLE NICHOLSON, OF NEW YORK, N. Y., ASSIGNOR TO JOHN L. CLARK, OF SAME PLACE.

WIRE BALE-TIE.

SPECIFICATION forming part of Letters Patent No. 315,821, dated April 14, 1885.

Application filed August 23, 1884. (No model.)

To all whom it may concern:

Be it known that I, GRANVILLE NICHOLSON, of the city and county of New York, in the State of New York, have invented a new and 5 useful Improvement in Wire Bale-Bands, of which the following is a specification.

My invention relates to wire bale-bands which have at one end an eye, and the other end of which is left plain and straight, so that 10 when the band is to be applied to a bale the plain end may be inserted through the eye and secured by bending it back and twisting it.

Various plans have been devised for securing a considerable body of metal in the eye, 15 whereby a broad band will be produced in the tail end of the wire when inserted through the eye and bent back upon itself, so that the wire will be less likely to break than if a sharp bend was there produced.

20 My invention consists in the combination, in a wire bale-band having at one end an eye, of a main or band wire, which is doubled or lapped once upon itself, and one or more re-enforcing pieces of wire, which are separate 25 and distinct from each other and from the band-wire, and which are doubled or lapped each upon itself and intertwined with the doubled or lapped portion of the main or band wire, as particularly hereinafter described, 30 and pointed out in the claim.

In the accompanying drawings, Figure 1 represents a view of the end portions of a bale-band connected or tied and embodying my invention. Fig. 2 represents the end portion 35 of the main wire lapped upon itself preparatory to forming the head and eye; and Fig. 3 represents a separate re-enforcing piece of wire, also lapped upon itself or doubled.

Similar letters of reference designate corresponding parts in all the figures.

A designates the main or band wire at one end, on the head of which is formed the eye A*, and the other or tail end, A', of which is in tying passed through the eye and then 5 bent back or lapped upon itself and twisted, as at a.

The component parts of the head end of the band, including the eye A*, are clearly shown in Figs. 2 and 3. If first bend back, double, or

lap upon itself the end portion, b, of the band-wire, as shown in Fig. 2, and may then provide one or more separate and distinct pieces of wire, B, such as are shown in Fig. 3, the piece being bent back, doubled, or folded upon itself, so as to form portions B B, which are approximately parallel. The re-enforcing piece B may then be incorporated with the lapping portions A b of the main or band wire by laying it thereon and intertwisting the parallel portions B B of the re-enforcing piece with the portions A b of the main or band wire. I thus form an eye, A*, which is double throughout, and when the tail end, A', is attached or tied a long bend, c, is formed therein, and will not be liable to break. I may employ a single 55 re-enforcing piece, as described, or two or even three such separate pieces, if desired, the parallel and lapping portions all being intertwined, as described, and in this way may make a band, the tail of which will be connected 60 with the eye by a very long or broad bend. The separate re-enforcing piece is also very 65 advantageous, because it may be made of wire larger or smaller than the main or band wire, and therefore a re-enforcing piece of 70 large wire may be incorporated with a band-wire of small size, thereby giving a sufficient body in the eye to avoid a short bend in the tail without making the band of large 75 wire throughout.

It will be understood from the foregoing description that the sole and only purpose of the re-enforcing piece or pieces, which are made separate from the band-wire, is to produce a large body of metal in the eye, so that when 80 the tail end of the band is inserted through the eye and bent back a broad easy bend will be produced in such tail end, and it will be less likely to break; hence it is advantageous 85 to incorporate a short re-enforcing piece of 90 wire of large size with a band-wire of comparatively small size.

What I claim as my invention, and desire to 95 secure by Letters Patent, is—

In a wire bale-band having at one end an eye, A*, the combination of the main or band wire A, having a portion, b, doubled or lapped upon itself, and one or more re-enforcing

pieces of wire, B, which are separate and distinct from each other and from the band-wire A, the re-enforcing pieces being each doubled or lapped upon itself and intertwisted with 5 the double or lapped portion of the main or band wire, substantially as herein described, whereby the main or band wire and the one

or more separate re-enforcing pieces of wire combine to form an eye in which is a comparatively large body of metal.

GRANVILLE NICHOLSON.

Correction in Letters Patent No. 315,821.

It is hereby certified that in Letters Patent No. 315,821, granted April 14, 1885, upon the application of Granville Nicholson, of New York, New York, for an improvement in "Wire Bale-Ties," errors appear in the printed specification requiring the following corrections, viz: In line 42, page 1, the comma after the word "end" should be omitted, and the following word, "on," should read *or*; and that the Letters Patent should be read with these corrections therein to make it conform to the record of the case in the Patent Office.

Signed, countersigned, and sealed this 5th day of May, A. D. 1885.

[SEAL.]

H. L. MULDROW,
Acting Secretary of the Interior.
